UNITED STATES PATENT OFFICE.

KARL VÖLLER, OF DUSSELDORF, GERMANY.

FIELD-GUN CARRIAGE.

1,090,767.

Specification of Letters Patent.

Patented Mar. 17, 1914.

Application filed June 27, 1913. Serial No. 776,173.

To all whom it may concern:

Be it known that I, KARL VÖLLER, engineer, a subject of the German Emperor, residing at 12 Scharnhorststrasse, Dusseldorf, 5 Germany, have invented certain new and useful Improvements in Field-Gun Carriages; and I do hereby declare the following to be a full, clear, and exact description of the invention, such as will enable others 10 skilled in the art to which it appertains to make and use the same.

The invention relates to an improved carriage for field guns, by which is to be understood in this connection any carriage, in 15 which the gun is transported and fired on wheels; the invention relates more particularly to guns, which have a very large horizontal range of fire and according to the invention no preparations are required before firing to insure lateral stability, by 20 folding down the sides of the carriage or setting up special supports, as is usually done in other constructions of this kind.

A large traverse is obtained by spreading 25 out the sides of the carriage at the rear and connecting them by a trail plate, which is constructed to act as a spade throughout its length. A tubular tail piece provided with a spade is pivoted to the trail plate and 30 serves as an extension of the carriage and provides sufficient stability, when firing with small elevation, for instance against targets on the battle field. The arrangement enables the gun to be easily transported in 35 spite of the large spread of the sides of the carriage and to be readily steered when limbered up. The spade on the trail plate may be toothed, so as to have a holding surface along all its length.

40 A construction according to the invention is shown in Figure 1 in side view and in Fig. 2 in a plan view from above.

The sides *a* of the carriage are, as seen in Fig. 2, spread out widely at the rear. They 45 are connected by a preferably curved trail plate *b*, which is constructed to act as a spade along all its length. A tubular extension *d* provided with a spade *e* is pivoted to the trail plate *b* by means of a pin *c*.

50 When a short carriage is fired at elevated targets the tail piece *d* is tilted upward and used as a hand spike. When firing at elevated targets considerable traverse must be allowed for, and it is important that care 55 should be taken to insure lateral stability;

this is attained in the present arrangement, since even when the traverse is great the aiming line always falls within the bearing surface of the spade or of the trail plate. In order that the carriage may be easily 60 moved through the soil the trail plate is curved in the arc of a circle. The center lies between the wheels near the middle of the axis or of the center of gravity *S* of the gun. The fore part of the carriage is narrowed to the ordinary dimensions, so that 65 the gun layers have room to carry out any operations on either side between the carriage and the wheels.

Having thus described my invention what 70 I claim is:

1. A field carriage for guns having an extended horizontal traverse, comprising, in combination with carrying wheels and an axle therefor, divergent side members secured to said axle, a continuous curved trail piece connecting said side members at their ends, and a spade extending from said trail piece approximately the full length thereof. 80

2. A field carriage for guns forming an extended horizontal traverse, comprising, in combination with carrying wheels and an axle therefor, divergent side members secured to said axle, a trail piece connecting 85 said members at their outer ends, said trail piece being formed on an arc struck from near the middle of the axis or center of gravity of the gun, and a spade forming part of said trail piece and extending approximately throughout its length. 90

3. A field carriage for guns forming an extended horizontal traverse, comprising, in combination with carrying wheels and an axle therefor, divergent side members secured to said axle, a trail piece connecting 95 said members at their outer ends, said trail piece being formed on an arc struck from near the middle of the axis or center of gravity of the gun, and a spade pivotally connected to said trail piece at the center thereof. 100

In testimony whereof, I have signed this specification in the presence of two subscribing witnesses.

KARL VÖLLER. [L. S.]
